UNITED STATES PATENT OFFICE.

IGNACY CERPIAL, OF SOUTH BEND, INDIANA.

WASHBOILER.

1,259,361.

Specification of Letters Patent. Patented Mar. 12, 1918.

Application filed March 24, 1917. Serial No. 157,119.

To all whom it may concern:

Be it known that I, IGNACY CERPIAL, a subject of the Czar of Russia, resident of South Bend, county of St. Joseph, and State of Indiana, have invented certain new and useful Improvements in Washboilers, of which the following is a specification.

This invention relates to improvements in domestic wash boilers, and has as its special object the provision of means in which clothes may be thoroughly boiled and brought into contact with cleansing solutions contained in the boiler without danger of scorching and without the escape of steam into the apartment.

A further object of the invention is to provide means combined with the boiler which permit of a thorough cleansing of the interior, whereby any accumulations may be removed.

These and other like objects are attained by the novel construction and combination of parts hereafter described and shown in the accompanying drawing, forming a material part of this specification, and in which:—

Figure 1 is a vertical sectional view taken through the center of the boiler.

Fig. 2 is a top plan view of the same, and Fig. 3 is a transverse sectional view taken on line 3—3 of Fig. 1.

The invention comprises an exterior cylindrical casing 10 having attached thereto a bottom plate 11 and provided with handles 13 and a wire beading 12 around its top edge.

An arcuate cover 14 having extending annular edges 15 is adapted to rest upon the beading 12 and has formed with it a cylindrical extension 16, the same being adapted to fit closely within the walls 10 of the boiler.

Transversely disposed between the handles 17 on the top of the arcuate cover 14 is a cup shaped vessel 18 through the center of which extends a valve 19 having a control handle 20 by which it may be operated, the lower side of the valve being engaged with a square tubular projection 22 adapted to extend downwardly within the boiler 10.

A circular plate 25 is disposed within the boiler 10, resting upon annular flanged edges 26, the plate having a plurality of fine per-

forations 27 formed through it so that the water contained in the chamber below the plate 25 can readily pass therethrough and mingle with the clothing disposed on it. 55

Secured centrally of the perforate plate 25 is a hollow cone 28, its upper end extending nearly to the top edge of the boiler 10, and containing a square opening receptive of the stem 22 by which the plate and cover 60 are relatively located.

Should an excess of pressure arise within the cone 28, it may pass outward through the passage within the square extension 22 when the valve 19 is opened. 65

In operation, the plate 27 being placed in position, the clothes are laid uniformly within the annular space contained between the cone 28 and interior walls 10 of the wash boiler, the cover 14 being applied in position. If it be desired to move the clothes so as to increase the circulation of the boiling water, the cover 14 may be rotated with reference to the casing 10, whereby moving the clothes to be washed is effected, and it will be 75 noticed that all excess or overflow from the square tube 22 is received within the cup 18 from whence it can be readily disposed.

It will be further evident that loosened particles from the soiled garments, together 80 with any solid, heavy material, will pass through the perforations in the plate 25 into the chamber below it and that the same are readily removed by raising the cone and attached plate. 85

I claim:—

In a boiler of the class described, the combination with a cylindrical vessel, a perforate plate supported therein, means permitting the withdrawal of said plate, said 90 means consisting of a hollow cone having a square opening in its upper point, an arcuate cover fitted to said vessel having a portion engageable within the walls thereof, a cup secured centrally of said cover, a hollow 95 square stem affixed in said cup and cover, said stem extending into the opening in the top of said cone, and means for opening or closing the passage through said extension.

In testimony whereof I have affixed my signature.

IGNACY CERPIAL.
